UNITED STATES PATENT OFFICE.

ISABELLA T. DE AJURIA, OF GLEN RIDGE, NEW JERSEY.

DESIGN FOR A RACK.

43,080.

Specification for Design.

Patented Oct. 1, 1912.

Application filed July 18, 1912. Serial No. 710,280. Term of patent 14 years.

To all whom it may concern:

Be it known that I, ISABELLA T. DE AJURIA, a citizen of the United States, and a resident of Glen Ridge, in the county of Essex and State of New Jersey, have invented a new and ornamental Design for Racks, of which the following is a specification, reference being had to the accompanying drawings, forming part thereof.

The figure is an isometrical perspective of a rack showing my new design.

I claim:

The ornamental design for a rack, as shown.

ISABELLA T. DE AJURIA.

Witnesses:

ELLA M. MARSHALL,
NATHAN RUSSELL, Jr.
